LADY'S FOOTCAP OR THE LIKE

Russell P. Kantor, New York, N. Y., assignor to Alex. Lee Wallau Inc., New York, N. Y.

Application November 28, 1951, Serial No. 17,544
Term of patent 14 years

(Cl. D7—7)

To all whom it may concern:

Be it known that I, Russell P. Kantor, a citizen of the United States of America, residing in New York, county of New York, and State of New York, have invented a new, original, and ornamental Design for a Lady's Footcap or the like, of which the following is a specification, reference being had to the accompanying drawing, forming part thereof.

Fig. 1 is a front perspective view of a lady's footcap or the like showing my new design.

Fig. 2 is a fragmentary view of the footcap showing the inside of the heel portion.

Fig. 3 is a rear elevational view.

I claim:

The ornamental design for a lady's footcap or the like, substantially as shown.

RUSSELL P. KANTOR.
